UNITED STATES PATENT OFFICE.

THOMAS ROWCROFT, OF PHILADELPHIA, PENNSYLVANIA, ASSIGNOR TO
THE STAR AND CRESCENT MILLS COMPANY, OF SAME PLACE.

HEDDLE MECHANISM FOR LOOMS.

SPECIFICATION forming part of Letters Patent No. 660,928, dated October 30, 1900.

Application filed March 30, 1900. Serial No. 10,763. (No model.)

To all whom it may concern:

Be it known that I, THOMAS ROWCROFT, a citizen of the United States, residing in Philadelphia, Pennsylvania, have invented certain 5 Improvements in Heddle Mechanism for Looms, of which the following is a specification.

The object of my invention is to so construct the heddle-operating mechanism of a 10 loom as to provide for changing the pattern at any desired intervals—an object which I attain in the manner hereinafter set forth, reference being had to the accompanying drawings, in which—

15 Figure 1 is a side view of heddle-operating devices for looms, illustrating the application of my invention thereto. Fig. 2 is an end view looking in the direction of the arrow, Fig. 1. Fig. 2^a is a view of a portion of the 20 structure, illustrating a continuation of that shown in Fig. 2. Fig. 3 is a side elevation, partly in section, looking in a direction the reverse of Fig. 1 and illustrating parts to which my invention particularly relates. Fig. 25 4 is an enlarged view, partly in elevation and partly in sectional plan, on the line *a a*, Fig. 1. Fig. 5 is a view illustrating a modification of part of my invention, and Fig. 6 is an enlarged view of part of the mechanism 30 shown in Fig. 1.

1 represents part of the fixed frame of the loom, upon which is mounted a transverse shaft 2, constituting the bearing for the series of heddle-levers 3, which are connected to the 35 heddles by means of straps 4 in the usual manner. The heddle-levers are vibrated by means of longitudinally-guided cam-slides 5, as shown in Fig. 6, each of said cam-slides having a pivoted jack 6, which is under 40 control of a pattern-lever 7, these pattern-levers being operated by rollers 8 upon a pattern-chain 9, which is moved to the extent of one link upon each pick of the loom by the action of a pawl 10, carried by an arm 11, hung 45 to the shaft of the pattern-chain, and acts upon a ratchet-wheel 10^a, secured to said shaft. The arm 11 is connected, by means of a rod 12, to one arm of a three-armed lever 13, which is operated by one of the cams 50 of the loom, and which likewise through the medium of rods 14 imparts reciprocating mo-

tion to the upper and lower slide-bars 15 and 16, whereby the jacks 6 are actuated, so as to impart reciprocating movement to the cam-slides 5, and hence effect the desired vibration of the heddle-levers. All of the parts thus far described are common to heddle mechanism now in use, my invention consisting of certain additions to such mechanism whereby the shedding of the heddles may be 55 changed and the pattern of the fabric thereby varied at desired intervals.

The pattern-chain 9 has its rollers 8 arranged in sets, each set covering a space on each bar of the chain equal to a width of two 60 or more rollers, depending upon the number of changes which it is desired to effect. In the present instance each set covers a width of three rollers and three lateral positions of the pattern-chain are provided for—that is 65 to say, the two extreme positions and an intermediate position.

There may be but one pattern-lever 7 for each of the sets of pattern-rollers, in which case the heddles corresponding to said pattern-levers will be operated in a certain order when controlled by one section of the rollers of a set, in another order when controlled by another section of the rollers of said set, and in still another order when controlled by the third section of the rollers of the set, or there may be more than one pattern-lever for each set of rollers of the pattern-chain, each lever being controlled by the rollers of the set which happen to be moved 80 beneath the same. The disposition of the pattern-levers and of the rollers of each set on the pattern-chain will be dependent upon the character of the patterns to be produced.

The shaft 18, carrying the notched wheels 85 or drums upon which the pattern-chain is mounted, is adjusted laterally in its bearing, such adjustment being effected in the present instance by means of a cam-slide 20, which acts upon a pair of collars or flanges 21 and 90 22, secured to said shaft 18, there being in the present instance upon both the inner and outer faces of the cam-slide cams 23 and 24, those on the inner face of the slide being adapted to act upon the collar 22 when the 95 cam-slide is moved in the direction of the arrow, Fig. 4, and those upon the outer face of

the cam-slide being adapted to act upon the collar 21 when said cam-slide is moved in a direction the reverse of that indicated by the arrow. Three different positions of the pattern-shaft and its chain are thus provided for.

As shown in Fig. 4, the pattern-chain is in one of its extreme positions, but by moving the cam-slide 20 in the direction of its arrow until the cams 23 have acted upon the collar 22 said pattern-chain will be moved to an intermediate position, and by a still further movement of the cam-slide in the direction of the arrow until the cams 24 have acted upon the collar 22 the pattern-chain will be moved to the opposite extreme position and the pattern-chain will be moved in the opposite direction by a reversal in the direction of movement of the cam-slide.

Movement is imparted to the pattern-slide 20 in the following manner: Hung to the slide is a jack 25, having hooks 26 and 27 on its upper face and other hooks 28 and 29 upon its lower face, and this jack is in the present instance supported by means of a pin 30, resting upon the upper face of a cross-bar 31, at the upper end of a vertical bar 32, which is suitably guided on the frame of the loom and is slotted at its lower end for the reception of a vertically-adjustable stud 33, which bears upon a lever 34, the latter in the present instance being connected both directly and by a link 35 to a bell-crank lever 36, which forms part of the drop-box-operating mechanism of the loom and is acted upon by studs upon the drop-box pattern-chain 37. The jack 25 has a series of holes 60 disposed in a line inclined in respect to the horizontal, any one of these holes receiving the pin 30, so as to vary the vertical relations of the jack 25 and cross-bar 31, as may be required. A pin 61 on the fixed frame serves by contact with the jack 25 to limit the rise of the same under the lifting action of the cross-bar 31.

Hung to the upper portion of the loom is a lever 38, which is vibrated in unison with the lever 13 by means of a rod 39, connecting the two, and the opposite arms of said lever 38 are connected by rods 40 and 41, respectively, to upper and lower reciprocating bars 42 and 43, which are intended to act, respectively, upon the hooked upper and lower faces of the jack 25, said bar 42 moving in one direction when the bar 43 moves in the opposite direction.

As shown in Figs. 1 and 3, the jack 25 is raised to its fullest extent and the cam-slide 20 occupies its outward limit of movement, the upper reciprocating bar 42 having acted upon the hook 26 of the jack 25 to move the slide to such extreme position. If it is now desired to move the cam-slide 20 from its outward extreme position to its inward extreme position, the jack 25 is, by movement of the bar 32, dropped to its full extent, so that the hook 28 of the jack will engage with the lower reciprocating bar 43 when the latter has been moved outward to its full extent. Hence on

the retraction of said bar 43 the jack 25 and cam-slide 20 will be moved with it to the full extent of the travel of said bar 43, which is sufficient to effect a movement of the cam-slide 20 from one extreme position to the other. 70

If it is desired to move the cam-slide 20 from its outer extreme position to an intermediate position, the jack 25 is only partially lowered, so as to bring its hook 29 into engagement with the bar 43. Hence part of the inward movement of said bar 43 will be lost and only the remaining portion of said movement will be imparted to the jack 25 75 and cam-slide 20, and the latter will only be moved to the intermediate position, movement of the slide from this position to the inward extreme position being effected by again dropping the jack 25, so that its hook 28 will be in position to engage with the bar 43. Outward movement of the cam-slide to the extent of a complete or partial throw is effected by lifting the jack 25, so that its hook 26 or 27 may engage with the reciprocating upper bar 42. The pattern-chain mechanism is firmly locked by the cams of the bar 20 in each of the positions to which it is adjusted. 80

The lever 34 is in the present instance 95 weighted, as shown at 62 in Fig. 2^a, so that its normal tendency is to lift the bar 32 to its full extent, the weight of said bar 32, its cross-bar, and the jack resting thereon being sufficient to cause the bar to descend when 100 the lever 34 is operated by the pattern-chain, although it will be manifest that there may be a positive connection between the lever 34 and the bar 32, so as to insure movement of said bar with the lever in both directions. 105

When the lever 34 is combined with the drop-box lever 36, change in heddle control may be effected simultaneously with a change in the character of the wefts applied, although this is not essential, as the lever 34 may, if desired, be entirely independent of the drop-box lever and may be operated by studs on the drop-box pattern-chain independent of those intended for the operation of said drop-box lever. 110

Movement of the cam-slide 20 by momentum beyond the position to which it is intended to adjust it is prevented by the action of a roller 45, carried by a lever 46, which is hung to a stud on the frame of the loom and is acted upon by a spring 47, tending to depress the roller 45 and cause it to engage with one or other of a series of recesses 48, 49, and 50, formed in the upper surface of the cam-slide 20, as shown in Fig. 3. 115

As before stated, the ratchet-wheel 10^a on the pattern-chain shaft 18 is operated by a pawl 10, carried by an arm 11, which is free to swing on the pattern-chain shaft, and this pawl-carrying arm moves laterally with the 120 shaft, and in order to permit this lateral movement the rod 12, whereby the pawl-carrying arm 11 is connected to the lever 13, is hung to a vertical pin 19 on said lever, so that

its outer end is free to swing laterally to accommodate the varying lateral positions of the arm 11.

Although in carrying out my invention I prefer to use the cam-slide as a means of effecting the lateral shifting of the pattern-chain shaft, certain features of my invention may be employed in connection with means other than the cam-slide for effecting such movement. For instance, in Fig. 5 I have shown a construction in which the cam-slide is replaced by a rod 20^a and a bell-crank lever 20^b, the rod 20^a being intended to be operated by the same means as those employed for operating the cam-slide and being attached to one arm of a bell-crank lever, the other arm of the latter engaging with cams 21^a and 22^a on the shaft 18 of the pattern-chain.

Having thus described my invention, I claim and desire to secure by Letters Patent—

1. The combination in heddle-operating mechanism for looms, of a laterally-movable pattern-chain having pattern-rollers in sets, the rollers of each set being disposed side by side, coöperating elements of the heddle mechanism, whereby either series of rollers of a set may be caused to act upon the coöperating element, and means for laterally moving the pattern-chain said means also locking the same in each of its positions of adjustment, substantially as specified.

2. The combination in heddle mechanism for looms, of a laterally-movable pattern-chain and means for effecting such lateral movement, comprising a slide movable in a direction transversely to the movement of the pattern-chain and having cams for imparting lateral movement to said pattern-chain, and collars on the pattern-chain carrier for engaging said cams, substantially as specified.

3. The combination in heddle mechanism for looms, of a laterally-movable pattern-chain, and means for effecting such lateral movement, said means comprising a slide movable in a direction transversely to the movement of the chain, and having cams upon its opposite faces, and flanges or collars on the pattern-chain shaft, one of said collars being acted upon by the cams on one side of the cam-slide and the other by the cams on the other side of said slide, substantially as specified.

4. The combination in heddle mechanism for looms, of a laterally-movable pattern-chain, and mechanism for effecting such lat-

eral movement, comprising a rod or bar mounted so as to reciprocate in a direction transversely to the movement of the pattern-chain, means whereby the movement of said rod or bar causes lateral movement of the chain, a hooked jack carried by said bar, a pair of reciprocating bars adapted to engage with said hooked jack, and means for moving said jack so as to cause a hook of the same to engage with either of said bars, substantially as specified.

5. The combination in heddle mechanism for looms, of a laterally-movable pattern-chain, a rod or bar movable in a direction transversely to said pattern-chain, means whereby the movement of said rod or bar is transmitted to said pattern-chain, a hooked jack carried by said bar, a pair of reciprocating bars adapted to engage with said hooked jack, and means for moving the jacks so that a hook of the same may engage with either of said reciprocating bars, said means having a cross-bar whereby the jack is supported and in respect to which it can move longitudinally without affecting its support, substantially as specified.

6. The combination in heddle mechanism for looms, of a laterally-movable pattern-chain, and mechanism for effecting such lateral movement, comprising a rod or bar movable in a direction transversely to the movement of the pattern-chain, means for transmitting the movement of said rod or bar to the chain, a jack carried by the bar, and having a series of hooks upon its upper and lower edges, a pair of reciprocated bars, one above and one below the jack, and means for moving the jack whereby either of its hooks may be caused to engage with a corresponding bar, substantially as specified.

7. The combination in heddle mechanism for looms, of a laterally-movable pattern-chain, a ratchet, a pawl, a swinging pawl-arm for operating the pattern-chain shaft, all partaking of the lateral movement of said shaft, and an operating-rod for said swinging pawl-arm having pivotal connection with its actuating device, whereby its outer end is free to swing laterally with the pawl-carrying arm, substantially as specified.

In testimony whereof I have signed my name to this specification in the presence of two subscribing witnesses.

THOS. ROWCROFT.
